DOOR MOUNT AND ACTUATOR

Gustav Elving Lundine, Jamestown, N. Y., assignor to Jamestown Steel Partitions, Inc., Falconer, N. Y., a corporation of New York

Application June 17, 1947, Serial No. 755,123

7 Claims. (Cl. 20—16)

1

This invention relates to improvements in cabinets and particularly to structure by which to mount and actuate the doors thereof.

The present invention is found to be well suited to the installation of doors of utility cabinets or cupboards wherein frequently required articles, such as food products, cleaning equipment, tools, etc., may be stored. Access to a cabinet or cupboard of this type, particularly when located in a kitchen, is very frequent, and a large door and opening are generally provided for greater convenience. It has been found, however, that these large doors are of the nature of a hazard as they are frequently left open, or swing open from a presumed closed position into that area of a room or passage in which a person may be required to move about. Of course, latches of various kinds may be provided for securing a door in closed position and also some type of spring utilized to move a door into latching position. The application of such structure to the door of a cabinet of this type is objectionable by reason of cost of installation and the nuisance that a person must hold the door open against the spring action with one hand while placing articles in, or removing them from a cabinet.

It is a purpose and object of the present invention to provide a simple and easily installed cabinet door pivot and actuator.

It is also an object of the invention to provide a door pivot that enables use of a small, inconspicuous spring structure as an actuator to urge a door into closed or opened position.

It is a further object of the invention to provide spring structure that will urge into and yieldingly hold a door in closed position and, when the door has been opened beyond a certain point, urge it into and yieldingly hold it in fully opened position.

Other objects and advantages of the invention will be more fully understood and appreciated from a consideration of the following specification, taken in conjunction with the accompanying drawings; and in which

Fig. 1 is a perspective view of an open door cabinet, one form of the invention being shown applied to mount and effect limited actuation of the door;

Fig. 2 is an enlarged fragmentary perspective view, partly in section, showing one of the pivotal supports and spring actuator for the door;

Fig. 3 is a fragmentary top view, partly broken away and sectioned, showing the spring holding the door in closed position;

Fig. 4 is a view similar to Fig. 3 and shows

2

the limit to which the door might be manually opened and automatically closed by spring action; and

Fig. 5 is a view similar to Fig. 3 showing the action of the spring to hold the door in opened position, the dot and dash lines suggesting the action of the spring to move the door into fully opened position.

Referring more particularly to the drawing, the 10 reference numeral 10 is employed to generally designate a cabinet or cupboard of the type to which the present invention is particularly well suited. The cabinet shown includes side walls 11, rear wall 12, top 13, and base 14. Although 15 of no particular importance to the present invention, the front edges of the side walls include flanges 16 that serve to slightly restrict the width of the cabinet access opening. The opening to the cabinet is closed by a door 17. In the present disclosure, the cabinet is shown to be constructed of metal and the door 17 therefor includes reinforcing flanges 18 on its marginal edges. For additional support at the point of pivotal connection, top and bottom reinforcing plates 19 may 20 be permanently secured to the inner face of the top and bottom flanges 18.

That portion of the base 14 that defines the bottom of the cabinet access opening is shown to include a sill 21 and an upstanding stop 22. Although the sill extends the full width of the opening, the stop flange 22 terminates short of one end, leaving a gap, indicated at 23 in Fig. 1.

The top of the access opening may be formed by a header strip 24 which includes a horizontal portion 26 and a depending stop flange 27. The flange 27 is in the same vertical plane as flange 22, and thus cooperates, when the door is urged in closed position, to cause its outer face to be substantially flush with the flanges 16 of the side panels 11. As indicated in Fig. 2, the flange 27 stops short of the horizontal portion 26, leaving an end gap 28 similar to the gap 23 of the sill. A strap spring 29 is mounted on the inner face of the flange 27 in any suitable manner, as by pins or rivets 31. This spring includes a flat portion 32 which abuts the flange 27, and a curved or arched portion 33. The portion 33 terminates in a somewhat rolled end 34, and these latter parts, as may be seen in the drawing, overlie the gap or cut-away 28.

In the present disclosure, the door 17 is provided with top and bottom pivot pins 36 that extend through suitable openings 37 in the horizontal portions of the sill and header. The pivotal point of the door, as identified by the

pins 36, is located considerably inwardly from one vertical door edge and forwardly toward the door face, substantially as shown in the drawing. The purpose of this may be readily understood from a comparative examination of Figs. 3, 4, 5. Herein it is evident that the rolled end of the spring (Fig. 3) exerts outward pressure on that portion of the door beyond the pin 36 and, thus, the remainder of the door on the other side of the pin is urged inwardly of the cabinet. It is not intended that the action of this spring be greater than enough to gently swing the door into fully closed position from the partially opened position suggested in Fig. 4. However, the action of the spring is sufficient at all times to hold the door against inadvertent opening. Thus, the spring not only serves the same purpose as a door latch or catch, but also always urges the door into closed position when it has been swung from fully opened to partially opened position.

Examination of Fig. 5 indicates that, when a user of the cabinet wishes to fully open the door, the spring will also serve to hold the door in fully opened position, since the spring is so contoured and the door pivot so located that the inwardly swinging portion of the door rides into and seats in the curved portion 33 of the spring. Of course, this is not a socketed seat that requires special means of release and, therefore, the door, while remaining in fully opened position, may be readily swung from this open position at least to the position shown in Fig. 4, from whence it will be closed by the pressure of the end of the spring. It will also be evident from the dot and dash line position of the door and spring in Fig. 5 that the pivotal relationship of the door to the spring is such that, when the door has nearly reached its fully opened position, the spring will urge the door into such position. It will be understood that one spring 28 might be adequate for the purposes set out above. However, since the springs are of comparatively small proportions, are not appreciably exposed to view, and are easily installed, it has been found preferable, in a cabinet having a door of the size shown in the drawing, to provide two springs, one at the top and the other at the bottom of the door.

From the foregoing it is evident that through the use of one or more strap springs a cabinet or cupboard door may be made to swing into and remain in fully opened or fully closed position, provided the door pivots are located substantially as set out and the reversely swinging portion of the door beyond the pivots is of such proportions as to be contacted by the spring in substantially the manner shown.

Although applicant has shown and described only one form of his spring and pivot structure for urging a door into and yieldingly holding it in either fully opened or closed position, it will be apparent that variations in the spring, spring mounting, and door pivots may be made and are contemplated insofar as they are within the spirit and scope of the invention as set out in the annexed claims.

Having thus set forth my invention what I claim as new and for which I desire protection by Letters Patent is:

1. In a cabinet having an access opening and a door adapted to close said opening; a door mount and actuator comprising a pair of pins extending beyond the top and bottom edges of said door, said pins being located adjacent the face of and somewhat remote from one ver-

tical edge, a sill and header forming base and top margins of said door opening and having apertures adapted to receive said pins, and spring means secured to at least one of said margins engageable with that portion of said door between said pins and the vertical door edge.

2. In a cabinet having an access opening defined in part by a sill and header, and a door adapted to close said opening; a door mount and actuator comprising top and bottom pivots carried by said door, said sill and header having apertures for receiving said pivots, said pivots and apertures being located inwardly from one vertical edge of said door, said door edge thus being swingable into the cabinet interior when said door is swung outwardly toward open position, and spring means secured to said cabinet and projecting into the path of and being engaged by said door edge and serving to urge said door into fully closed position.

3. In a cabinet, a header and sill defining the top and bottom of an access opening, a door adapted to close said opening, top and bottom pivot pins on said door set inwardly of the door edge a distance greater than the door thickness, said header and sill having apertures for receiving said pins, and a spring attached to said header, an end portion of said spring having pressure contact with the edge portion of said door adjacent the top pivot pin.

4. In a cabinet, a header and sill defining the top and bottom of an access opening, a door adapted to close said opening, top and bottom pivot pins on said door, said header and sill having apertures for receiving said pins, said pins being so located inwardly of one vertical edge of said door to enable said one vertical edge to swing into the cabinet interior beyond said header and sill when said door is moved to opened position, a spring attached at one end to said header, the other end of said spring normally having pressure contact with said door edge, and an intermediate portion of said spring and said door edge being interengageable to yieldingly hold said door in a fully opened position.

5. In a cabinet, a header and sill defining the top and bottom of an access opening, a door adapted to close said opening, a stop flange on said header for determining the closed position of said door, top and bottom pivot pins on said door, said header and sill having apertures for receiving said pins, said stop flange having a slot adjacent the location of its pivot pin aperture, a strap spring secured at one end to that portion of said flange adjacent said slot, the other end of said spring projecting into said slot and normally having pressure contact with the pivoted edge portion of said door, said spring serving to yieldingly hold said door in abutment with said stop flange.

6. In a cabinet, a header and sill defining the top and bottom of an access opening, a door adapted to close said opening, a stop flange on said header for determining the closed position of said door, top and bottom pivot pins on said door, said header and sill having apertures for receiving said pins, said pins and apertures being so located as to cause the adjacent door edge to swing into the cabinet interior when said door is opened, said stop flange having a slot adjacent the location of its pivot pin aperture, a strap spring, a flat end portion of said spring being secured to said flange adjacent said slot, the other end of said spring being aligned with said slot, an intermediate recessed portion of said

spring adapted to receive said door edge and yieldingly secure said door in fully opened position.

7. In a cabinet, a header and sill defining the top and bottom of an access opening, a door adapted to close said opening, a stop flange on said header for determining the closed position of said door, top and bottom pivot pins on said door, said header and sill having apertures for receiving said pins, said pins and apertures being so located as to cause the adjacent door edge to swing into the cabinet interior when said door is opened, said stop flange having a slot adjacent the location of its pivot pin aperture, a strap spring, a flat end portion of said spring being secured to said flange adjacent said slot, the other end of said spring normally projecting into said slot and having a curved portion terminating in

a rolled edge, said spring edge having pressure contact with the pivoted edge of said door and serving to urge said door from a partly opened position into closed position in abutment with said stop flange, said curved portion, when said door approaches opened position, functioning to urge said door into and yieldingly hold it in fully opened position.
